Primary Examiner — Ryan Harvey(74) *Attorney, Agent, or Firm* — Michael Best & Friedrich LLP(57) **CLAIM**

The ornamental design for a dice randomizer, as shown and described.

DESCRIPTION

FIG. 1 is a front perspective view of a dice randomizer showing my new design;

FIG. 2 is a front plan view thereof;

FIG. 3 is a rear plan view thereof;

FIG. 4 is a left side elevational view thereof;

FIG. 5 is a right side elevational view thereof;

FIG. 6 is a top elevational view thereof; and,

FIG. 7 is a bottom elevational view thereof.

The broken line showing of portions of the dice randomizer depicts environment and forms no part of the claim.
